G. O. DEGENER,

COMBINED TYPE WRITING AND COMPUTING MACHINE.
APPLICATION FILED NOV. 25, 1912.

APPLICATION FILED NOV. 25, 1912.

1,270,750.

Patented June 25, 1918.

UNITED STATES PATENT OFFICE.

GUSTAVE O. DEGENER, OF NEW YORK, N. Y., ASSIGNOR TO UNDERWOOD COMPUTING MACHINE COMPANY, OF NEW YORK, N. Y., A CORPORATION OF NEW YORK.

COMBINED TYPE-WRITING AND COMPUTING MACHINE.

1,270,750.

Specification of Letters Patent. Patented June 25, 1918.

Application filed November 25, 1912. Serial No. 733,244.

To all whom it may concern:

Be it known that I, GUSTAVE O. DEGENER, a citizen of the United States, residing in New York city, in the county of New York

5 and State of New York, have invented certain new and useful Improvements in Combined Type-Writing and Computing Machines, of which the following is a specification.

10 This invention relates to combined type-writing and computing machines. One of the objects of the present invention is to provide simple means for preventing operation of the numeral keys at a punctuation 15 point occurring in a computing column; another feature is the provision of simple means for silencing said preventing means when computation is not going on; and still another feature is a provision for simultaneous adjustment of the computing column 20 and said preventing means, by adjustment of a single part.

The improvements are especially adapted to be used in machines of the class set forth 25 in the pending application of Wright and Degener, No. 485,030, filed March 22, 1909. In said application, the computing wheels are power-driven, and the movements of said wheels are controlled by means of an escapement mechanism operated by the keys. In 30 said application, the connection between the numeral keys and said escapement mechanism is established by means of hooks which engage said numeral keys, and these hooks, 35 when the keys are operated, swing bell cranks, which operate the escapement mechanism.

The machine disclosed in said application is herein shown as combined with a locking 40 device, such as is shown in my prior Patent No. 1,010,349, dated November 28, 1911, in which patent each numeral key is connected through its hook to a blade so that when any one key is operated, its blade will prevent the operation of any other numeral 45 key until the first key is in its normal idle position. Said blades for this purpose are arranged to be swung radially across the axis of a cylinder so that all said blades 50 intercept said axis at the same point. The result is that when any of said blades is swung across the axis no other blade can be so swung until the first one is returned to normal position, and since each blade is 55 connected to its numeral key, the blades

make it impossible for one numeral key to be operated unless every other key is in its normal idle position.

The carriage of the typewriter may include a tappet which is arranged to automatically swing a controlling arm to connect the computing mechanism to the numeral keys of the typewriter by means of the above described hooks. This tappet may be also caused to lock the numeral keys 60 against operation at selected letter-spaces, as for example at every fourth letter-space in pointing off "thousands" in a long number. This may be accomplished by varying the throw of said controlling arm, for example, 70 by causing an overthrow of said controlling arm at said fourth letter-spaces.

The locking device of my prior patent, above cited, may be utilized to lock the numeral keys by such overthrow. For this 75 purpose the locking device may include a blade operated by such overthrow, but otherwise like the numeral key blades, so that when swung to interfering position across the axis of the cylinder, it will prevent the 80 operation of any numeral key. It will be seen that when such blade is in such interfering position, while no numeral key can be operated, the other keys, such as the comma or space key may be operated if desired, because such keys have no interfering 85 blade attached to them.

By having a single tappet on the typewriter carriage thus control the connections from the numeral keys to the computing 90 mechanism and to the above described locking device, it will be seen that any adjustment of the tappet for one purpose will automatically adjust the mechanism for the other. 95

The invention may also include means for manually disconnecting the computing mechanism from the controlling arm, and said disconnecting mechanism may be of the general type shown in the application, No. 100 485,030 above described, which type enables the connection between the controlling arm of the typewriter and the numeral keys to be so set, that said arm may be either effective or ineffective to control said connection. 105

As shown in said patent, this manual disconnecting device may operate the hooks for the numeral keys. It thereby simultaneously moves to ineffective position all connection from the locking blades and the 110

other parts of the computing mechanism to the numeral keys, and so entirely frees the typewriter from the computing mechanism and its locks.

5 Other features and advantages will hereinafter appear.

In the accompanying drawings,

Figure 1 is a perspective view of so much of a combined Underwood-Wright typewriter and computing machine as is necessary to illustrate my invention.

Fig. 2 is a detail of the key-locking means.

Fig. 3 shows the manual disconnecting means in a different position from that seen 15 in Fig. 1.

Fig. 4 is a front view of the controlling arm.

Fig. 5 is a plan view showing said arm and its relation to the tappets.

20 Fig. 6 is a detail of the interfering device.

A numeral key 1 of the typewriter, by means of type (not shown) prints on a platen (not shown) on a carriage comprising a rack 2 of the typewriter. Said carriage is drawn along one letter-space at a time by the operation of the keys and may likewise be positioned by means of a tabulating device comprising plungers (not shown) in a casing 3 at the rear of the typewriter frame, said plungers co-operating with column stops 4 which may be adjustably set on the rack bar 2.

The numeral keys of the typewriter may be connected by means of hooks 5 arranged to underlie elbows 6 on the key levers so as to swing bell cranks 7 to control the computing mechanism. For controlling said mechanism each bell crank comprises a downwardly extending arm 8 joined by a link 9 to an elbow lever 10; each elbow lever having pivoted thereon a jack 11 which is arranged to project a pin 12 in a primary escapement wheel 13, and the projection of this pin determines the number which is to be carried into the computing mechanism.

As the link 9 is drawn by the numeral key 1, a head 14 on said link engages a universal disk 5, so as to rock a secondary escapement device comprising dogs 16 and 17, so as to 50 cause the number registered or set up by the projected pin 12 to be carried into the computing wheels (not shown herein).

The connections between said dogs and the disk 15 include a stem 18 extending from said head, and said head is arranged to swing, by means of a pin 19 embracing a lever 20, the opposite end 21 of said lever, so as to draw a link 22 by the said end, and rock a rock arm 23 fast on the shaft 24 to 60 which shaft the dogs 16 and 17 are likewise fast.

The primary escapement wheel 13 is constantly under tendency to turn by means of a motor (not shown herein), so that a previously projected pin 25 bears against one

arm of a star wheel 26 on a shaft 27, the other end of which shaft carries teeth 28, which teeth are intercepted by the dogs 16 and 17.

When a numeral key 1 is depressed, the 70 dog 16 is rocked to the right, as viewed in Fig. 1, so that the tooth 28 which has been bearing against said dog slips past the edge of said dog and strikes the dog 17. On the return stroke of the numeral key the dogs 75 16 and 17 are rocked to their position, as seen in Fig. 1, but meantime the tooth 28 has escaped past the edge of dog 17 on the return stroke of said dog, so as to permit the projected pin 25 to turn the star wheel, 80 and the primary escapement wheel 13 therefore turns until the pin 12, which has been just projected, is intercepted by the tooth of the star wheel 26. Meantime the tooth 25, which had been previously projected, is 85 returned within the primary escapement wheel by means of a cam (not shown). The disk 15 is drawn backward on the return stroke of the numeral key by means of a spring 30 surrounding one end of its stem 18. 90

A gear wheel 29 fast on the escapement wheel 13 carries into the computing mechanism (not shown) the numbers recorded in the above described manner.

The hooks 5 may be swung clear of the 95 elbows 6 of the numeral keys, so that said numeral keys may be operated idly, so far as the computing mechanism is concerned. For this purpose said hooks are embraced by a bar 31 which is pivoted to a manually 100 operated connecting and disconnecting device, as seen at the left hand of Fig. 1 and in Fig. 3.

The bar 31 is connected to a shifting lever 54 at 54^a so that the latter can manipulate 105 the bar 31 when it is rocked about its pivot, indicated at 57.

The shifting lever 54, which forms an element of the shifter, is not itself directly operated manually. To enable the operation 110 of the shifting lever 54 there is provided a manual controller, which in this instance is shown in the form of a pair of co-operating sector gears 56 and 57^a mounted on pivot pins 57 and 59. One of these sector gears 56 115 is provided with a handle or button 55, which extends to the front of the machine where it can be readily manipulated to change the position of the parts of the controller, and thus change the action of the 120 controller.

When the parts of the controller are in the position indicated in Fig. 1, a spring 52, which is attached at its ends to pins 51 and 53, located respectively on the sector gear 125 57^a and the shifting lever 54, will be under a tension tending to draw the sector gear 57^a and the shifting lever 54 toward each other. The sector gear 57^a, however, is prevented from movement in such a direction 130

by means of a stop 49, shown in the form of a pin secured to the sector gear 57^a, and engaging a toe 48 on a lever 47, which forms a part of the compensating or opposing mechanism, and which is shown to be loosely mounted on the pivot 57 on which the shifting lever 54 is also loosely mounted.

The movement of the shifting lever 54 is also prevented by a stop arm 60 thereon 10 overlying and engaging a pin 61 on the compensating lever 47. The pin 61 has secured thereto a spring 62, which is secured at its upper end to a fixed pin 63. The spring 62 pulls stronger than the spring 52, 15 so that it prevents the movement of the shifting lever 54, under the pull of the spring 52 by holding the compensating lever 47 immovable against the pull brought thereon through the stop arm 60. It will be 20 seen, however, that the movement of the shifting lever 54 in the direction of pull of the spring 62, and thus the movement of the floating interponent or compensating lever 47, under the pull of the spring 62, is limited 25 by one arm 58 of the upper bifurcated end of the shifting lever 54 engaging the pivot 59 or the extension thereof, as indicated in Fig. 3. The other arm 58 of the bifurcation will likewise limit the movement 30 of the shifting lever 54 in the opposite direction, as indicated in Fig. 1.

In order to do any computing it is necessary to overcome the opposition of the spring 62, and thus permit the spring 52 to 35 manipulate the shifting lever 54 from the position indicated in Fig. 1 to the position indicated in Fig. 3. For this purpose, an automatic control by the typewriter carriage is provided. The pin 61 has connected there- 40 to a link 46, which is secured at its lower end to an arm 44 of a shaft 45 extending rearwardly where it is provided with a second arm 43. The arm 43 is connected by a link 42 to a controlling bell-crank lever 38, 45 operated by the typewriter carriage.

The above described operation of the bell-crank 38, by means of the typewriter carriage, is brought about by means of cams 32 and 33, which are arranged to be inter- 50 cepted by an extension 34 on the stop 4, forming a tappet to move said cams. Said cams are adjustably mounted so as to form a continuous edge or cam on the arm 35, fast on the rock shaft 36, journaled in 55 brackets 37, fast on the casing 3 of the tabulating mechanism, which rock shaft carries said bell-crank lever 38. Said lever 38 carries a bent portion 39, which underlies a rock arm 40, near the pivot 41 of said rock shaft, 60 the link 42 being attached to said rock arm 40.

By having the bent end 39 of the bell-crank 38 to operate the rock arm 40 near its pivot 41, it will be seen that the small throw 65 of the cams 32 and 33 by the tappet 4 will

cause a relatively large motion of the outer end of the rock arm 40, and thereby give the link 42 a considerable throw, which throw operates the link 31 as above described.

Even while the cam 35 is in engagement with one of the tappets 4, so that the typewriter carriage tends to make the hooks 5 engage the numeral keys 1, the hooks 5 can be disconnected from the numeral keys at 75 such times as it may be desired. To do this, it is merely necessary to rotate the sector gears 56 and 57^a from the position shown in Fig. 1 to the position shown in Fig. 3, in which position the sector gears will be held 80 by the spring 52 being shifted to the other side of the pivot 57, and tending to pull the shifting lever 54 and the sector gear 57^a toward each other. This movement of the sector gears 56 and 57^a is, however, limited by 85 providing the enlarged teeth, shown in Fig. 3, at the engaging ends of the sectors. The pin 49 will be shifted to the position indicated in Fig. 3, so that it will be out of engagement with the toe 48, and, therefore, 90 there will be no pull on the sectors 56 and 57^a. The spring 62, however, will still act, through the intermediary of the pin 61 and the stop arm 60, to force the shifting lever 54 into the position indicated in Fig. 3. 95 Even if the carriage-controlling mechanism, acting through the tappet 4 and cam 35, should be actuated, there will therefore be no tendency to bring the shifting lever from its disconnecting position to its connecting 100 position, so that the typewriting mechanism can be actuated without actuating the computing mechanism.

In the operation of the device, if it is desired to use the computing mechanism as 105 well as the typewriting mechanism, the parts are manipulated so as to occupy the position indicated in Fig. 1, in which the spring 52 will be under a tension normally tending to shift the lever 54, and thus the 110 bar 31, so as to bring the hooks 5 into connection with the numeral keys 1. This action, however, is normally prevented by the spring 62, which is so connected as to exert a stronger pull on the arm 60 than is exerted by the spring 52, thus holding the hooks in the position indicated in Fig. 1. As soon as the carriage, however, has been moved, either by actuation of character keys or tabulating keys, or by hand, to a 120 position corresponding to a column on the work-sheet in which it is desired to compute, then one of the tappets 4, which has been previously placed in a corresponding position on the rack bar 2, will come into 125 engagement with the controlling cam 35, so as to force the same away from the rack 2 until the bearing surface of the cams 32 or 33 rests on the extension 34 of the tappet 4. This movement will, through the con- 130

necting linkages, pull down on the pin 61 against the tension of the spring 62. The spring 52, being now relieved of the superior tension of the spring 62, will exert its power 5 to draw the hooks 5 into engagement with the elbow 6 on the key levers 1. It will thus be seen that not only is the tension of the spring 62 overcome by the pull of the link 46, but the tension on the spring 52 is aided 10 by the action of the toe 48 on the pin 49, slightly rotating the sector 57^a.

In my prior Patent No. 1,010,349 above referred to, means are shown for preventing the simultaneous operation of two numeral 15 keys. Said means include an extension blade 64 fast on each of the elbow levers 10, which extension blades extend through slots 65, as seen in Figs. 1 and 6, in a cylindrical member 66. Said slots are radially 20 arranged, and the extension blades 64 all pass the axis of said cylinder at the same point, and each is moved inward by the operation of its numeral key. From this it results that when any numeral key is depressed, 25 its blade 64 will occupy the center of the cylinder 66 and so prevent any other numeral key from being depressed.

In the present invention these blades are utilized to prevent the operation of a numeral key at any space in a computation 30 where other characters than figures should be written, as for example, commas. For this purpose there is provided a blade 67 which may be identical with the blade 64, 35 but is connected to be swung by overthrow of the cams 32 and 33, so that every time said cams are overthrown, the blade 67 will prevent the operation of any blade 64 and so prevent the operation of any numeral 40 key. For so swinging the blade 67, it is provided with a link 68 having a slotted head 69, which, unlike the heads 14, does not operate the universal disk 15, being shorter than said heads 14, as seen in Figs. 45 1 and 2. It will therefore be seen that movement of the link 68 will merely swing the blade 67 into locking position, as shown in Fig. 2.

The link 68 is operated from the arm 54 by means of an idle arm 70 carrying pins 71, which lie on either side of the arm 54, and so engage with said arm but permit of considerable lost motion. Said lost motion is so arranged that the ordinary 55 movement of the arm 54 in swinging the bar 31 is not sufficient to cause said link 68 to swing its blade 67. If, however, the arm 54 is overthrown a considerable distance to the left, the arm 68 will swing its blade 67 60 to the locking position seen in Fig. 2. For so swinging said arm 54 to overthrow position, the cam 32 carries a block 72 removably attached thereto, which block comprises rollers 73 arranged to intercept the tappet 65 34 and so move the cams 32 and 33 to a

greater extent than the cam faces themselves would so move said cams. It will therefore be seen that by having the rollers 73 spaced at say every fourth letter-space, numbers could be written and pointed off in "thousands," every fourth letter-space being a comma. 70

The amount of lost motion between the pins 71 and the bar 54 must be so proportioned that when the bar 54 is returned by the spring 62 after the tappet 34 has passed a cam roller 73, the blade 67 will be positively moved from its effective position seen in full lines in Fig. 2, to its normally ineffective position, as seen in dotted lines in 80 said figure. The amount of lost motion is likewise shown in said Fig. 2, and the length of the head 69 is also indicated as being insufficient to operate the universal disk 15, but the link 68 rides in a slot in said disk 85 and is supported thereby.

The cams 32 and 33, as will be seen from Fig. 4, comprise slots 74 through which screws 75 pass, entering threaded openings 76 in the rock arm 35 so that said cams 90 may be adjustably mounted on said rock arm. The block 72 is mounted on the cam 32 by means of screws 77 threaded into the cam 32.

Variation may be resorted to within the 95 scope of the invention, and portions of the improvements may be used without others.

Having thus described my invention, I claim:

1. In a combined typewriting and computing machine, the combination with numeral keys, a traveling carriage and a computing device controlled by said keys, of means for preventing the operation of more than one of said numeral keys at a time 100 during computation, a member operated by the travel of the typewriter carriage and co-operating with said preventing means for preventing the operation of any numeral key at a selected point in the travel of said carriage, and a single means operable at will for both disconnecting said keys and rendering said member ineffective to lock said keys at said point. 105

2. In a combined typewriting and computing machine, the combination with numeral keys and a computing device, of a traveling carriage, a tappet on said carriage, an arm moved by said tappet, means controlled by said arm to connect said keys 110 to said computing device, and means for moving said arm differently by said tappet to lock said keys against operation at a selected letter-space in the travel of said carriage. 115

3. A combined typewriting and computing machine having a traveling carriage, numeral keys, computing mechanism, and a connection between said numeral keys and computing mechanism; and comprising, in 120

combination, means for controlling the connection between said keys and said computing mechanism at any part of the carriage travel, and means moved by said controlling 5 means for preventing operation of said keys at selected letter-spaces.

4. In a combined typewriting and computing machine, the combination with numeral keys and a computing device, of a 10 blade operated by each numeral key, a member in which said blade swings, so that when one blade is operated no other numeral key can be operated, and a blade controlled by the typewriter carriage for preventing the 15 operation of any other of said blades at any letter-space adjustably determined in the travel of said carriage.

5. In a combined typewriting and computing machine, the combination with numeral keys and a computing device, of a 20 traveling carriage, a tappet on said traveling carriage, an arm swung by said tappet to connect said keys to said computing device, a device for arresting the operation of 25 any numeral key, and means for operating said arresting device by the overthrow of said arm.

6. In a combined typewriting and computing machine, the combination with numeral keys and a computing device, of a 30 hook for each numeral key to connect it to said computing device, a bar for moving said hooks to effective or ineffective position, an arm on which said bar is pivoted, 35 a device settable to prevent the operation of any numeral key, a link for operating said device, and a lost motion member for connecting said link to said arm, so that the overthrow of said arm will operate said preventing device.

7. In a combined typewriting and computing machine, the combination with numeral keys and a computing device, of a hook for each numeral key for connecting 45 it to said computing device, a bar for swinging said hooks, elbows on said keys arranged to coöperate with said hooks, so that said hooks may be considerably overthrown when in effective position, and means for preventing the operation of a numeral key by 50 said overthrow.

8. In a combined typewriting and computing machine, the combination with numeral keys and a computing device, of a 55 combined device for preventing the simultaneous operation of two keys and for locking said keys against operation, and means including a single handle for connecting said keys to said computing device and to 60 said combined device.

9. In a combined typewriting and computing machine, the combination with numeral keys and a computing device, of a 65 traveling carriage, a tappet on said traveling carriage, a cam operated by said tappet,

and rollers on said cam operated by said tappet to increase the swing of said cam.

10. In a combined typewriting and computing machine, the combination with numeral keys and a computing device, of a 70 traveling carriage, a tappet on said carriage, a cam moved by said tappet, means controlled by said cam for connecting said keys and computing devices, a combined device for preventing the simultaneous operation of two keys and for locking all said keys against operation, and means including a handle for controlling said means between said keys and said computing device and for rendering operative or inoperative 75 said combined device.

11. In a combined typewriting and computing machine, the combination with numeral keys and a computing device, of a 80 traveling carriage, a connection between each key and the computing device, means for preventing said keys from operating, means including an arm moved by a tappet on said carriage to connect said keys to said computing device and to operate said preventing means, and means including a handle for setting said connections so that they may be inoperative even if said tappet is in position on said carriage.

12. In a computing machine, the combination with numeral keys and computing devices, of a member common to all of said keys and means controlled by said member when it is moved to one position to control the connection between said computing devices and said keys, and means controlled by said member when moved to another position, to lock all of said keys from operation.

13. In a combined typewriting and computing machine, the combination with numeral keys and a traveling carriage, of a 95 computing device, means under control of said carriage for preventing normal operation of a numeral key, locking means connected to said keys for coöperating with said preventing means, connecting means between a key and said computing device, means for making and breaking said connecting means to thereby render said carriage-controlled preventing means ineffective when said keys are disconnected from said computing device.

14. In a combined typewriting and computing machine, the combination with numeral keys and a traveling carriage, of a 100 computing device, means to lock said keys against operation, a tappet on said carriage, means including an arm moved by said tappet, to control the connection of said keys 105 to said computing device, and means on said arm to control said key-locking means at a selected letter-space in the travel of said carriage.

15. In a combined typewriting and com- 110

- puting machine, the combination with a traveling carriage and a tabulating stop, of numeral keys, computing devices, means for connecting said keys to said computing devices, a cam under the control of said tabulating stop for operating and maintaining said connecting means in a certain zone, and means for preventing the operation of any of said numeral keys at a predetermined point in said zone, and also under the control of said stop. 16. In a computing machine, the combination with numeral keys and computing devices, of means for connecting said keys to said devices, and means for moving said connecting means farther to prevent the operation of any key so connected. 17. The combination with a typewriter carriage, of printing keys, computing devices connectible to said keys, a cam, a dog on said carriage to be effective on said cam, means controlled by said cam to connect said computing devices to said keys, and means whereby said dog is effective on said cam to make said keys inoperable. 18. The combination with a typewriter carriage, of printing keys, computing devices connectible to said keys, a cam, a dog on said carriage to be effective on said cam, means controlled by said cam to connect said computing devices to said keys, and devices on said cam whereby said dog is effective on said cam to make said keys inoperable at certain points only. 19. The combination with a typewriter carriage, of printing keys, a computing device controlled by said keys, a cam extending along several letter-spaces of the travel of said carriage, a dog on said carriage to be effective on said cam, and a connection from said cam to makes said keys inoperable in a selected column in the run of said carriage. 20. The combination with a typewriter carriage, of printing keys, computing wheels controlled by said keys, devices connectible to said keys, a cam, a dog on said carriage to be effective on said cam, means controlled by said cams to connect said devices to said keys, and means whereby said dog is effective on said cam to make said keys inoperable through the medium of said devices. 21. The combination with a typewriter carriage, of printing keys, computing wheels controlled by said keys, devices connectible to said keys, a cam, a rack bar on said carriage, a dog on said rack bar to be effective on said cam, means controlled by said cam to connect said devices to said keys, and devices on said cam whereby said dog is effective on said cam to make said keys inoperable through the medium of said last-named devices. 22. In a computing machine, the combination with keys and computing wheels, of a traveling carriage, a cam under the control of said carriage, means controlled by said cam for connecting said keys to said wheels, an extension adjustable on said cam for varying its length, means including devices connectible to said keys for preventing their operation at a predetermined time, and members mounted on said extension for selecting said predetermined time. 23. In a computing machine, the combination with keys and computing wheels, of a traveling carriage, a cam under the control of said carriage, means controlled by said cam for connecting said keys to said wheels, an extension adjustable on said cam for varying its length, means including devices connectible to said keys for preventing their operation at a predetermined time, members mounted on said extension for selecting said predetermined time, tabulating stops on said carriage, and extensions on certain of said stops whereby said carriage controls said cam. 24. In a computing machine, the combination with keys and computing wheels, of a traveling carriage, a cam under the control of said carriage, means controlled by said cam for connecting said keys to said wheels, an extension adjustable on said cam for varying its length, means including devices connectible to said keys for preventing their operation at a predetermined time, members mounted on said extension for selecting said predetermined time, a bar for connecting said keys and devices, a handle for shifting said bar, and a spring whereby said handle draws on said bar. 25. In a computing machine, the combination with numeral keys, of key-interfering devices for preventing simultaneous operation of two keys, a carriage for said machine, a tabulating device, and means to enable the tabulating device to control the connection between said keys and interfering devices. 26. In a computing machine, the combination with numeral keys, of key-interfering devices for preventing simultaneous operation of two keys, a device for preventing the operation of any numeral key, normally ineffective connections between said keys and said first-named devices, and a carriage-operated cam and means controlled thereby for connecting said keys and first-named devices, and rendering operative said second-named preventing device. 27. In a computing machine, the combination with numeral keys, of key-interfering devices for preventing simultaneous operation of two keys, a device for preventing the operation of any numeral key, normally ineffective connections between said keys and said first-named devices, a carriage-operated cam, means controlled by said cam for connecting said keys and first-named devices, 130

members on said cam and means controlled by said members for rendering the last-named device effective.

28. In a combined typewriting and computing machine, the combination with numeral keys, of computing devices controlled thereby, a series of interfering devices, one for each key, for preventing the simultaneous depression of more than one key, another interfering device coöperating with said first-mentioned interfering devices and serving through such coöperation to lock all of said keys, means for connecting said keys and computing devices in the computing zone, and means for disconnecting said keys and said computing devices in the computing zone, said means also rendering said second-named interfering device ineffective to lock said keys.
29. A combined typewriting and computing machine having a traveling carriage, computing mechanism, and keys controlling both; and comprising, in combination, means for locking all of said keys when the carriage is in certain positions in the computing zone, resilient means tending to move said locking means to key-locking position, means controlled from said carriage for permitting said resilient means to lock said keys, and means operable at will for rendering said carriage-control ineffective to lock said keys in the computing zone by altering the action of said resilient means.
30. A combined typewriting and computing machine having a traveling carriage, computing mechanism, and keys controlling both; and comprising, in combination, connections from the keys to the computing

mechanism, means for locking all of the keys at certain positions of the carriage, resilient means tending to move said key connections to connect said keys and computing mechanism and move said locking means to key-locking position, and means controlled by said carriage for permitting said resilient means to act to connect said keys and said computing mechanism in certain parts of the computing zone, and to further act to lock all of said keys against operation in certain other parts of the computing zone.

31. A combined typewriting and computing machine having a traveling carriage, computing mechanism, and keys controlling both; and comprising, in combination, connections from the keys to the computing mechanism, means for locking all of the keys at certain positions of the carriage, resilient means tending to move said key connections to connect said keys and computing mechanism and move said locking means to key-locking position, means controlled by said carriage for permitting said resilient means to act to connect said keys and said computing mechanism in certain parts of the computing zone, and to further act to lock all of said keys against operation in certain other parts of the computing zone, and means for rendering the carriage control inoperative to control the key connections and the locking means by altering the action of said resilient means.

GUSTAVE O. DEGENER.
